UNITED STATES PATENT OFFICE.

ROBERT L. SHANNON, OF MCKEES ROCKS, PENNSYLVANIA, ASSIGNOR OF ONE-HALF TO
EDWARD McFARLAND, OF MCKEES ROCKS, PENNSYLVANIA.

GUARD FOR TURNING-MACHINES.

1,156,559.

Specification of Letters Patent.

Patented Oct. 12, 1915.

Application filed May 6, 1914. Serial No. 836,785.

To all whom it may concern:

Be it known that I, ROBERT L. SHANNON, a citizen of the United States of America, residing at McKees Rocks, in the county of Allegheny and State of Pennsylvania, have invented certain new and useful Improvements in Guards for Turning-Machines, of which the following is a specification, reference being had therein to the accompanying drawing.

This invention relates to a guard for turning machines and has for its object to provide a device of such class, in a manner as hereinafter set forth, for protecting the operator from the cuttings during the operation of the turning tool.

Further objects of the invention are to provide a turning tool, which is simple in its construction and arrangement, strong, durable, efficient and convenient in its use, readily set up with respect to the tool, and inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a front elevation of a guard in accordance with this invention showing the adaptation thereof in connection with the tool carrier and work. Fig. 2 is a sectional plan of Fig. 1, and Fig. 3 is a vertical sectional view, on line 4—4, of Fig. 1 and on a smaller scale.

Referring to the drawings in detail 4 denotes the work, as illustrated a wheel, upon a support 5 and arranged in proximity to the work is a tool carrier consisting of an upright 6 having projecting therefrom an upper pair of clamping bolts 7 and a lower pair of clamping bolts 8.

Mounted upon the bolts 7 and 8 are washers 9 and nuts 10.

The reference characters 11 and 12 denote a pair of clamping bars which at their tops are formed with transverse slots 13 and at their bottoms with vertical slots 14. The

bars 11 and 12 are adapted to be mounted upon the bolts 8, the slots 14 providing for such purpose and are also mounted upon the bolts 7, the slots 13 providing for such purpose.

The tool, which is indicated at 15, is mounted below the bolts 7 and above the bolts 8 or upon the bolts 8 and the tool 15 is maintained in position by the bars 11 and 12, which in connection with the washers 9 and nuts 10 clamp the tool 15 against the upright 6.

Each of the bars 11, 12 has its upper inner corner beveled as at 16 to facilitate the positioning of the cross head 27, to be hereinafter referred to, when coupling the guard 18, to be hereinafter referred to, in position with respect to the tool.

Associated with and capable of being detachably coupled with the bars 11 and 12, is a guard support and which consists of an arm 17 extending at a plane at right angles with respect to the bars 11 and 12. One end of the arm 17 is provided with a vertically disposed hollow semi-cylindrical guard 18, the latter being closed at its top and open at its bottom and cut away as at 19 to provide a clearance for the flange 20 of the work. The guard 18 and arm 17 is reinforced through the medium of a pair of spaced straps 21, which is fixedly secured to the outer face of the arm 17 and to the outer face of the guard 18. Connected to the arm 17 between the straps 21 is a handle 22.

Fixedly connected to the straps 21 and extending at right angles with respect thereto is a vertically disposed bar 23, bifurcated at its upper and lower ends as at 24 and pivotally connected in each of said bifurcated ends as at 25, is a link 26 having its inner end provided with a cross head 27. The cross heads 27 are adapted to be forced against the inner corners of the bars 11 and 12 whereby the guard support will be detachably connected in position so that the guard will be arranged close up to the work and close up to the cutting end of the tool 15. The frictional engagement between the cross heads 27 and bars 11 and 12, is such to prevent the shifting of the cross heads 27 under normal conditions and is furthermore such to maintain the guard support in position under normal conditions. When the cross heads 27 are shifted to the position shown in Fig. 3, they will not, under normal

conditions, drop downward, and set up a clamping action.

What I claim is:—

- 5 1. A guard for boring machines comprising a vertically disposed elongated semi-cylindrical hollow guard member, a support therefor, a tool carrier and means for detachably connecting said support with the tool carrier to position the guard in close proximity to one side of the work and the cutting end of the tool.
- 10 2. A guard for turning machines comprising a hollow vertical elongated guard member, a support therefor, a tool carrier and means carried by the support for detachably connecting the latter with the tool carrier to position the said member in close proximity to one side of the work and cutting end of the tool.
- 15 3. A guard for turning machines comprising a guard member, a support therefor, a bar connected with said support, and means

carried by the bar and capable of engaging with the tool carrier for detachably securing said member to said carrier and further 25 for maintaining the member in proximity to the work and the cutting end of the tool.

4. A guard for machines comprising a guard member, a support therefor, a bar connected with said support, a tool carrier 30 arranged on said support, means carried by the bar and engaging with the tool carrier for detachably securing said member to said carrier and further for maintaining the member in proximity to the work and the 35 cutting end of the tool, and a handle for said support.

In testimony whereof I affix my signature in the presence of two witnesses.

ROBERT L. SHANNON.
